UNITED STATES PATENT OFFICE.

ALFRED EINHORN, OF MUNICH, GERMANY, ASSIGNOR TO THE FIRM OF C. H. BOEH.
RINGER SOHN, OF NIEDER INGELHEIM, GERMANY.

GUAIACOL CARBONATE SULFO-ACID DERIVATIVE

938,132.

Specification of Letters Patent. Patented Oct. 26, 1909.

No Drawing.

Application filed June 22, 1908. Serial No. 439,842.

To all whom it may concern:

Be it known that I, ALFRED EINHORN, citizen of Germany, residing at Munich, Bavaria, Germany, have invented certain new and useful Improvements in the Art of Making Guaiacol Carbonate Sulfo-Acid Derivatives; and I do hereby declare the following to be a full, clear, and exact description of the invention, such as will enable others skilled in the art to which it appertains to make and use the same.

This invention relates to the manufacture of guaiacol sulfo-acid derivatives and in particular to the preparation of the salts of the sulfo-acids of guaiacol carbonate.

The objects of the invention are to obtain such salts of this character as are adapted for therapeutic purposes, and which can be used together with ferric preparations without inconvenience, producing no color reactions with them as is the case with guaiacol sulfo-acid salts, and which, moreover, are more pleasant to the taste than the latter.

With these objects in view my invention consists in the class of compounds herein-after described and claimed and also in the process for making them as hereinafter described and covered in the claims.

I have found that the salts of the mono- and di-sulfo acids of guaiacol carbonate, which are soluble in water, are formed when phosgen acts upon guaiacol sulfo acids or upon mixtures of guaiacol and a guaiacol sulfo acid in the presence of alkalies and their known substitutes, as, for instance, bases of pyridin etc., according to the following formulae:

Up to now it has not been possible to produce carbonates of acid derivatives of the phenols, although this has been frequently attempted, more especially from salicylic acid. In the German patent specification No. 117346, page 1, at the bottom, it is, for instance, stated that according to the process there described heptasalicylosalicylic acid

and tetrasalicylid are formed from salicylic acid, but in no case the carbonate of salicylic acid. In coöperation with Gustav Haas (*Berichts der Deutschen Chemischen Gesellschaft*, vol. 38, page 3627; see also his dissertation, Munich 1905, pages 15 and 30) it was pointed out that salicylic acid is not acted upon at all by phosgen in the presence of alkali carbonates or hydrates. It was therefore to be expected that the sulfo acids of guaiacol would, when treated with phosgen, behave similarly to salicylic acid, and it could not be foreseen that the very reverse would take place, and that they are capable of forming carbonates, in spite of the acid sulfo group.

Salts of the sulfo acids of guaiacol carbonate have heretofore remained unknown. In the German patent specification No. 94078 salts of the sulfo acids of the aliphatic creosote ester are described. These, however, are in no way uniform, and are most probably mixtures of several salts. Since they give a color reaction when treated with ferric chlorid, and separate the sulfo group when heated with caustic solutions, and further change to amino derivates when treated with ammonia, they are obviously not what they have been supposed to be, but belong rather to a totally different class of combinations from the salts of the mono- and di-sulfo acid of guaiacol carbonate, which give no color reaction with ferric chlorid and which do not, when heated with ammonia and caustic solutions, separate the sulfo group.

The salts of the sulfo acids of guaiacol carbonate are intermediate between the two preparations of guaiacol most used for medicinal purposes, namely, the guaiacol carbonate and the guaiacol sulfo acid salts (for instance, thiocol). In contra-distinction to guaiacol carbonate they have the advantage of being easily soluble in water, and compared with thiocol they taste better and give no color reaction with ferric salts and can therefore be used in combination with ferric preparations for medicinal purposes.

Example I: Phosgen is passed into a cooled solution consisting of 5 grams of the potassium salt of guaiacol sulfo acid (thiocol) and 3 grams of caustic potash in 27 grams of water, until an acid reaction is shown; hereby the greater mass of the potassium salt of guaiacol carbonate disulfo acid is directly precipitated, and the remainder can

be separated from the filtered solution with chlorid of potassium. The potassium salt of guaiacol carbonate di-sulfo acid crystallizes out of a watery solution, and it gives no color reaction with ferric chlorid, and does not reduce silver nitrate solutions, whereby it is distinguished from the potassium salt of guaiacol sulfo acid (thiocol). From diluted alcohol it separates in the form of needles; in methylic alcohol it is only very slightly soluble and in ethylic alcohol quite insoluble: Neither hydrochloric acid nor sulfuric acid alter the concentrated watery solution of the salt.

15 Example II: Phosgen is passed into a cooled solution consisting of 20 grams of the potassium salt of guaiacol sulfo acid (thiocol) and 10.4 grams of guaiacol in 120 grams of a 10% solution of caustic potash until an acid reaction takes place; thereby a precipitate is formed, which is then filtered, dried and digested with acetic ether, which dissolves the resulting guaiacol carbonate. The residue is now dissolved in 25 hot water, from which, on cooling, the potassium salt of guaiacol carbonate mono-sulfo acid separates in the form of crystals, and finally, when alcohol is added to the filtered solution, the potassium salt of guaiacol carbonate di-sulfo acid is precipitated.

For purifying, the potassium salt of guaiacol carbonate mono-sulfo acid is crystallized out of a watery solution, from which it separates in the form of fatty, lustrous, 35 prismatic crystals; with ferric chlorid it gives no color reaction; from diluted alcohol, in which it dissolves with difficulty, it crystallizes in the form of small lustrous needles; from methylic alcohol, in which it is only 40 with difficulty soluble, it separates in the form of long needles, and from absolute alcohol, in which it is only soluble with the greatest difficulty, it separates as microscopic indistinct crystals. An addition of hydrochloric acid or sulfuric acid to a concentrated solution of the salt produces no 45 change.

The products obtained by this process are to be used for therapeutic purposes.

50 What I claim as my invention and desire to secure by Letters Patent, is:

1. The process for the production of a salt of guaiacol carbonate sulfo-acids, which consists in causing phosgen to react on an alka-

line bath containing the potassium salt of 55 guaiacol sulfo-acid until the bath reacts acid.

2. The process for the production of a salt of guaiacol carbonate sulfo-acids, which consists in passing phosgen into a cooled aqueous bath of a salt of guaiacol sulfo-acid 60 together with an alkali, until the bath reacts acid.

3. The process for the production of a salt of guaiacol carbonate sulfo-acids, which consists in passing phosgen into a cooled aqueous bath of a salt of guaiacol sulfo-acid together with an alkali, until the bath reacts acid, then separating the resulting precipitate and finally treating the remainder of the bath with a halogen salt of an alkali. 70

4. The process for the production of a salt of guaiacol carbonate sulfo-acids, which consists in passing phosgen into a cooled aqueous bath of a salt of guaiacol sulfo-acid together with an alkali, until the bath reacts acid, 75 then separating the resulting precipitate and finally treating the remainder of the bath with potassium chlorid.

5. As a new chemical compound, a salt of a sulfo-acid of guaiacol-carbonate, having 80 the following properties: It is easily soluble in water and gives no color reaction with ferric salts and, when heated with ammonia or with caustic alkali solution, does not split off the sulfo-group. 85

6. As a new chemical compound, an alkali metal salt of a sulfo-acid of guaiacol-carbonate which has the properties of being easily soluble in water and giving no color reaction with ferric salts and, when heated 90 with ammonia or with caustic alkali solution, does not split off the sulfo-group.

7. As a new chemical compound the potassium salt of the disulfo-acid of guaiacol-carbonate, which crystallizes out of water 95 and dilute alcohol, which crystallizes out of the latter in the form of pointed needles, is only slightly soluble in methyl-alcohol and insoluble in concentrated ethyl-alcohol, which gives no color reaction with ferric salts and which is not altered by dilute mineral acids but is altered by alkalies. 100

In testimony whereof I hereunto affix my signature in the presence of two witnesses.

ALFRED EINHORN.
